UNITED STATES PATENT OFFICE.

HERMAN A. WILLIAMS, OF PALMS, CALIFORNIA, ASSIGNOR, BY DIRECT AND MESNE ASSIGNMENTS, TO LEONARD C. MYERS, OF LOS ANGELES, CALIFORNIA.

AUTOMOBILE CURTAIN-WINDOW.

1,334,824.

Specification of Letters Patent. Patented Mar. 23, 1920.

Application filed July 15, 1918. Serial No. 244,837

To all whom it may concern:

Be it known that I, HERMAN A. WILLIAMS, a citizen of the United States, residing at Palms, in the county of Los Angeles 5 and State of California, have invented certain new and useful Improvements in Automobile Curtain-Windows, of which the following is a specification.

This invention relates to improvements 10 in curtain windows, and particularly to that class of windows which provide means for securing a plate of glass into a flexible curtain of automobiles and capable of producing a neat appearance and a water tight 15 joint around the frame of the window.

It is an object of the invention to produce a window construction having registering frames which grip the fabric of the curtain in such a manner as to not wrinkle or stretch 20 the threads of the said fabric out of their natural position as the frames are drawn together by screws or any suitable means commonly known in the art.

It is a further object to form the frame 25 of the window preferably of two members, one member being used on the inside of the curtain and the other member being used on the outside of the curtain. The outside member having means for holding a pane 30 of glass and the inside member adapted to register with the outside member and fasten to the same, the fabric of the curtain being clamped between the two members forming a cushion for the said glass 35 whereby all the parts are securely held together and without any danger of breaking the glass from the jar of the car.

Another important object is to form 40 grooves, depressions or indentations in the adjacent faces of the said members or rings of the frame, so related to one another, that the gripping of the fabric between the said rings presses the surface thereof into the said indentations and holds it fast when the 45 frame is set in place in the curtain of the automobile.

In window frames heretofore built where the tongue and groove and other systems have been employed to make the separable 50 members register, serious trouble has been experienced in getting the tongues to properly enter the grooves and at the same time stretch the fabric therearound and make a neat appearance of the curtain. This trouble 55 is entirely overcome in this frame as the

gripping surfaces of the inner and outer frame members are flat whereby the natural lines of the threads of the fabric are unchanged but are allowed to enter the depressions adjacent thereto and when the 60 members are fastened together and the fabric depressed into the said depressions, the window is safely held in place and as the depressions do not change the contour of the 65 edge of the members, a tight joint is formed around the outer edge thereof leaving the curtain smooth and unwrinkled.

With these and other objects in view the invention comprises certain novel constructions, combinations of parts as will be hereinafter more fully described and claimed:

In the accompanying drawing—

Fig. 1, is an outside elevation of part of a curtain showing a window secured in place with certain parts broken away.

Fig. 2, is a cross sectional view through the curtain and window taken on line 2—2 of Fig. 1.

Fig. 3, is a portion of an inner and outer ring, the outer ring broken away to show 80 the indentations of the inner ring.

Fig. 4, is a portion of the two rings showing the indentations of the outer ring.

Fig. 5, shows a ring having a modified form of indentations.

Fig. 6, shows a cross sectional view of a modified form of frame.

Fig. 7, is a cross sectional view taken on the line 7—7 of Fig. 6.

Referring more particularly to the drawing, the curtain 10 has an outer ring or member 11 positioned thereon, which is provided with a rabbet 12 on the under side and running entirely around the member. Seated in the rabbet 12 is a plate of glass or transparent member 13 having its edge 14 in the same plane as the flat surface 15 of the member 11, thus producing approximately a continuous surface for the fabric 10 to lie against.

Registering with the member 11 is an inside ring or member 16 co-operating therewith which has a flat surface 17 lying against the fabric 10, but on the opposite side thereof from the member 11. Securely 105 pressing and holding the two members together are screws or fastening means 18 which extend through the ring 16 and thread to a seat into the ring 11 whereby a pressure may be exerted upon the fabric 110

or flexible material 10 held between the two members.

The flat surfaces 15 and 17 of the rings 11 and 16 respectively, are provided with 5 grooves, depressions or indentations 19 and 20, these indentations are preferably set at an angle as shown by the drawing. The outer ring indentations 19 being of one angle while those of the other ring being of 10 an angle opposite thereto, as is plainly shown by Figs. 3 and 4 of the drawing.

After the window is completely assembled on the curtain and the frames drawn tightly together by the screws, the fabric is gripped 15 between the surfaces 15 and 17 and the structure of the fabric is forced into the depressions or indentations 19 and 20 whereby the portions of the curtain forced into said depressions cannot slip past the sharp edges 20 thereof or get away from the rings and the edge 21 forms a water tight joint around the entire window while the curtain is smooth and unwrinkled.

The modified form shown in Fig. 5 of the 25 drawing, is a ring with grooves or indentations 22 which would be ample for use of only one ring, whereby the forcing of the fabric into the indentations of a varied design something similar to that shown, would 30 prevent the slipping of a curtain after the two registering rings were fastened together.

The modified form shown in Figs. 6 and 7 of the drawings shows an outside ring 23 with the usual rabbet 24 holding a plate of 35 glass 25. The said ring 23 has indentations

26. Secured to the member 23 is a backing ring or member 27 which is preferably of wood. Lying between the two rings is an outside curtain 28. This curtain is gripped between the two rings by forcing the screws 40 29 to their seats, thereby pressing the fabric into the indentations 26 and holding the window permanently in place. The ring 27 has recesses 30 formed therein to receive lugs 31, the registering of these lugs with the 45 recesses properly center the two rings so as to facilitate the assembling of the parts.

To cover the wooden ring an inside curtain 50 32 is fastened thereto by any suitable means, as by tacks 33, thus finishing the curtain on the inside of the car.

The form and depth of the indentations or grooves may be varied, also the configuration of the frames and the details of construction without departing in the least 55 from the spirit and scope of the invention

What is claimed is:

A window frame construction comprising registering members having adjacent flat faces with grooves therein, a fabric curtain 60 lying between said faces, the angle of the grooves of one face being approximately at right angles to the angle of the grooves of the other face and means for drawing said faces together for forcing the fabric into 65 said grooves.

In testimony whereof I have hereunto set my hand.

HERMAN A. WILLIAMS.
